(57) **CLAIM**

The ornamental design for a display screen with graphical user interface, as shown and described.

DESCRIPTION

FIG. 1 is a front view of a display screen with a graphical user interface showing a new ornamental design.

FIG. 2 is a front view of a display screen with a graphical user interface showing a second embodiment thereof.

FIG. 3 is a front view of a display screen with a graphical user interface showing a third embodiment thereof.

FIG. 4 is a front view of a display screen with a graphical user interface showing a fourth embodiment thereof.

FIG. 5 is a front view of a display screen with a graphical user interface showing a fifth embodiment thereof.

FIG. 6 is a front view of a display screen with a graphical user interface showing a sixth embodiment thereof.

FIG. 7 is a front view of a display screen with a graphical user interface showing a seventh embodiment thereof.

FIG. 8 is a front view of a display screen with a graphical user interface showing an eighth embodiment thereof.

FIG. 9 is a front view of a display screen with a graphical user interface showing a ninth embodiment thereof.

FIG. 10 is a front view of a display screen with a graphical user interface showing a tenth embodiment thereof; and,

FIG. 11 is a front view of a display screen with a graphical user interface showing an eleventh embodiment thereof.

The outermost broken-line rectangle illustrates the perimeter of a display screen and forms no part of the claimed design. The remaining broken lines illustrate portions of a graphical user interface and form no part of the claimed design.
